HANDLE FOR A REFRIGERATOR DOOR LATCH

Charles W. Sanders, Greenville, Mich., assignor to
Gibson Refrigerator Company, Greenville,
Mich., a corporation of Michigan

Application February 6, 1951, Serial No. 14,109

Term of patent 14 years

(Cl. D67—3)

To all whom it may concern:

Be it known that I, Charles W. Sanders, a citizen of the United States, residing at Greenville, in the county of Montcalm and State of Michigan, have invented a new, original, and ornamental Design for a Handle for a Refrigerator Door Latch, of which the following is a specification, reference being had to the accompanying drawings, forming a part hereof.

In the drawings:

Figure 1 is a front view of a handle for a refrigerator door latch, embodying my new design;

Figure 2 is a side view of the same;

Figure 3 is a bottom view of the handle; and

Figures 4 and 5 are cross-sectional views taken on substantially the lines 4—4 and 5—5 respectively of Figure 2.

I claim:

The ornamental design for a handle for a refrigerator door latch, as shown.

CHARLES W. SANDERS.
